IDENTIFICATION BADGE

Harold W. Draper, West Orange, N. J., assignor
to The Whitehead & Hoag Company, Newark,
N. J., a corporation of New Jersey

Application February 8, 1941, Serial No. 377,956

5 Claims. (Cl. 40—1.5)

This invention relates to an identification badge and more particularly to an identification badge which will be relatively secure against unauthorized alterations or tampering therewith.

The objects of the invention will appear from the following description and the accompanying drawing in which

Fig. 1 is a front view of an assembled badge embodying the invention;

Fig. 2 is a rear view of the assembled badge shown in Fig. 1;

Fig. 3 is a side view of the assembled badge in section taken along the line 3—3 of Fig. 2;

Fig. 4 is a rear view of the face plate of the badge shown in Fig. 1;

Fig. 5 is a front view of the back plate of the badge shown in Fig. 1;

Fig. 6 is a plan view of the removable section of the back plate of the badge shown in Fig. 1;

Fig. 7 is a front view of an assembled badge in a modified form embodying the invention;

Fig. 8 is a side view of the badge shown in Fig. 7 in section taken along the line 8—8 of Fig. 7; and

Fig. 9 is a rear view of the face plate of the badge shown in Fig. 7.

Referring to the drawing in detail, the identification badge illustrated in Fig. 1 has a face plate 11 and a back plate 12 which are secured together by rolling the edges of the face plate 11 to extend over the back plate 12 to form a retaining flange 13 which holds the back plate 12 to the face plate 11.

The face plate 11 has apertures 14 and 15, and identifying devices 16 and 17 held between the face plate 11 and the back plate 12, are visible through such apertures. Access to identifying device 17 is provided by having a removable section 18 in the back plate. This removable section 18 has lugs 19 which fit into the pockets formed by indentations 20 in the back plate 12 so as to interlock the section 18 with the back plate 12. The removable section 18 is further secured in place by a rivet 21 which extends through the removable section and the face plate, the rivet, of course, having headed portions on the outside of the face plate and the outside of the section 18.

The rivet 21 forms a semi-permanent means for securing the removable section 18 in place. By removing the rivet 21 the interlocking means on the removable section 18 and the back plate 12 can be disengaged and the removable section 18 can be lifted from the back plate 12 and the identifying device 17 can be changed without disturbing other portions of the identification badge. The other identifying device 16 may be separated

from the enclosure for the identifying device 17 by having the portion of the face plate dividing the apertures 14 and 15 bent inwardly to form a barrier 22 between the adjacent enclosures for the identifying devices.

In such an identification badge the securing of the back plate 12 to the face plate 11 by the rolled flange 13 is of a permanent nature and the two plates cannot be separated without damaging either the flange 13 or the back plate 12 in such a way that it would be readily apparent.

To provide for changes in the identification devices when desired, the removable section 18 is provided which is secured in place in a semi-permanent manner by the rivet 21. This rivet 21 cannot be removed without visibly damaging it but it may be removed by authorized persons and replaced with a similar rivet with a certain amount of ease. If desired, an impression can be made in the rivet heads to insure that the rivet is not tampered with.

For the purpose of securing the badge to clothing or the like, a customary pin and clasp fastener 23 is secured to the back plate 12.

25 A modified form of badge is shown in Figs. 7—9 in which there is a face plate 24 having an aperture 25 through which an identifying device 26 is visible. The identifying device 26 is held between the face plate 24 and a back plate 27. This back plate 27 is removably secured to the face plate 24 by a turned over flange 28 which extends part way around the face plate 24 with which the back plate 27 enters into interlocking engagement and by a rivet 29 which extends through the back plate 27 and the face plate 24, the rivet 29 being headed on opposite sides of the respective plates.

When it is desired to change the identifying device 26, the rivet 29 will be removed so that the back plate may be removed from engagement with the flange 28.

While preferred embodiments of the invention have been shown and described it is to be understood that various changes may be made in construction by those skilled in the art without departing from the scope of the invention as defined in the appended claims.

I claim:

1. An identification badge comprising a face plate having apertures therein, a back plate secured to the face plate, identifying devices held between the plates and visible through the apertures, means separating the identifying devices from each other, a removable section in the back plate positioned to permit changing of an identi-

fying device, and means to secure the section semi-permanently in position, comprising interlocking means on the back plate and the removable section engaging with each other and securing means acting in cooperation with the interlocking means to hold the section against unauthorized removal.

2. An identification badge comprising a face plate having apertures therein, a back plate secured to the face plate, identifying devices held between the plates and visible through the apertures, a removable section in the back plate positioned to permit changing of an identifying device, and means to secure the removable section in position, said means comprising interlocking means on the back plate and the removable section engaging with each other, and securing means acting in cooperation with the interlocking means to hold the section against unauthorized removal.

3. An identification badge comprising a face plate having apertures therein, a back plate secured to the face plate, identifying devices held between the plates and visible through the apertures, means separating the identifying devices from each other, a removable section in the back plate positioned to permit changing of an identifying device, and means to secure the removable section in position, said means comprising interlocking means on the back plate and the removable section engaging with each other, and a rivet extending through the section and the front plate and acting in cooperation with the interlocking means to hold the removable section against unauthorized removal.

4. An identification badge comprising a face plate having an aperture therein, a peripheral flange extending around said face plate, an identifying device visible through the aperture in the face plate, a removable plate supporting the identifying device, said identifying device and removable plate lying beneath the edge of said flange at one end, said flange extending over and engaging with a portion of the removable plate at said end and semi-permanent fastening means acting in cooperation with said flange to secure said removable plate and identifying device to the face plate at the other end, said fastening means being capable of receiving identifying characteristics to prevent unauthorized removal of the fastening means.

5. An identification badge comprising a face plate having an aperture therein, a peripheral flange extending around said face plate, an identifying device visible through the aperture in the face plate, a removable plate supporting the identifying device, said identifying device and removable plate lying beneath the edge of said flange at one end, said flange extending over and engaging with a portion of the removable plate at said end and semi-permanent fastening means acting in cooperation with said flange to secure said removable plate and identifying device against unauthorized removal, said means comprising a rivet extending through said plates and having its headed portion on the outer sides thereof, at least one of said headed portions being capable of receiving identifying characteristics.
